UNITED STATES PATENT OFFICE.

HENRY LAWRENCE GULLINE, OF GRANBY, QUEBEC, CANADA.

FOLDING BOX OR CRATE.

No. 909,586.

Specification of Letters Patent.

Patented Jan. 12, 1909.

Application filed December 27, 1904. Serial No. 238,520.

To all whom it may concern:

Be it known that I, HENRY LAWRENCE GULLINE, of Granby, Province of Quebec, Canada, have invented certain new and useful 5 Improvements in Folding Boxes or Crates; and I do hereby declare that the following is a full, clear, and exact description of the same.

My invention relates particularly to boxes 10 or crates for use in the shipment or storage of fruit and other perishables or the like, and it has for its object to provide a folding box or crate with all four sides and its two ends permanently secured together, and with 15 its interior plane with single angles at each corner and without interior projections of any kind. For full comprehension, however of the invention, reference must be had to the accompanying drawings forming a part of this specification in which like symbols indicate corresponding parts, and wherein—

Figure 1 is a perspective view of a box 20 constructed according to my invention; Fig. 2 is a top view thereof in the act of being folded; Figs. 3 and 4 are top and end views, respectively folded; Fig. 5 is a top view of the box ready for use; Fig. 6 a longitudinal horizontal sectional view; Fig. 7 an enlarged sectional view of one corner and illustrating the pivotal connection of the top with the one side; Figs. 8 and 9 are side and end elevations, respectively; and Figs. 10 and 11 longitudinal and transverse sectional views respectively.

My improved folding box or crate consists of a pair of end sections, two side portions, a top, a bottom, and four corner posts, the latter serving as a means for pivotally connecting the ends to the sides, the end sections being the same in every respect, as are 35 also the sides and the top and bottom.

Each end consists of one or more body pieces *h* with top and bottom bars *b* and *c*, secured thereto and having their ends 40 rounded as at *d*, such body pieces being secured at their ends to the inside edges of the bars, *b* and *c*, into which they are preferably countersunk as shown in Fig. 3.

Each side consists of a pair of vertical bars, *i*, having secured to one side edge of each, one or more longitudinal body pieces, *j*, which are preferably countersunk thereinto as shown in Fig. 2. These side body pieces are equal in width to the space between the top and bottom bars *b* and *c* and

the vertical bars *i* are equal in height to the ends of the box or crate and therefore project a short distance above and below the side body pieces *j*.

The top consists of a body piece *m* and a 60 pair of longitudinal bars, *k*, and *l*, at the edges adjoining the sides of the box, and such top is pivotally secured by pins *n* projecting from the ends of bar *l* into eyes in the bars *i* of the rear side *j*. The bottom also 65 consists of a body piece *m'* and longitudinal bars *k'* and *l'* and is pivoted, by pins *o* projecting from bar *k'*, to the bars of the other side.

In order to connect the ends to the sides, 70 corner posts *e* are secured rigidly to the inner faces of the sides, and the top and bottom bars *b* and *c* are pivoted at *g* to the ends of such posts which latter are rounded throughout their length as at *e'* to allow the 75 body pieces *h* of the ends to turn with the bars *b* and *c* on their pivots *g*, which bars also have their ends rounded as at *d* to permit movement for folding.

What I claim is as follows:—

1. A folding box or crate composed of 80 two end sections, two side portions, a top, a bottom, and corner posts for connecting the end sections to the side portions; the end sections being provided with top and bottom bars pivotally connected to said corner posts; the side portions being secured to the said corner posts; bars *i* secured along the exterior of the end edges of the side portions and having their ends projecting 90 beyond the side edges of the said side portions and overlapping the ends of the said top and bottom bars; the said top and bottom having bars secured along the side edges thereof and abutting and being pivotally 95 connected to the projecting ends of the bars *i*, substantially as described.

2. A folding box or crate composed of 100 two end sections, two side portions, a top, a bottom, and corner posts; each end section being constructed of a body piece with top and bottom bars each side portion being constructed of a body piece with vertical 105 end bars; the top and bottom being each constructed of a body piece with longitudinal bars, one of such bars of the top being pivotally connected to the end bars of one side portion, and one of the bars of the bottom being pivotally connected to the bars of the other side portion; the said corner 110

posts being secured rigidly to said side portions, and the ends of the said top and bottom bars being pivoted to such corner posts.

3. A folding box or crate composed of 5 two end sections, two side portions, a top, a bottom, and corner posts; each end section being constructed of a body piece with top and bottom bars having rounded ends; each side portion being constructed of a 10 body piece with vertical end bars; the top and bottom being each constructed of a body piece with longitudinal bars, one of such bars of the top being pivotally connected to the end bars of one side portion, 15 and one of the bars of the bottom being pivotally connected to the end bars of the other side portion; the said corner posts being secured rigidly to said side portions, the rounded ends of the said top and bottom bars pivoted to such corner posts and the latter being rounded to allow of the working of the body pieces of the end sections; 20 substantially as described.

4. A folding box of the type having side

members, end members, and top and bottom 25 members all hinged together the end members being each pivotally connected at its opposite sides to the side members; each of such side, end, top, and bottom members presenting when the box is closed protruding 30 external bars arranged in the form of a protecting rectangular frame projecting laterally from the edges of each of the said side, end, top and bottom members the sides of each of the said rectangular protecting frames forming component parts of 35 the said members of the box with the body pieces of the ends and sides and top and bottom countersunk at all four sides of each into such rectangular frames. 40

In testimony whereof, I have signed my name to this specification, in the presence of two subscribing witnesses.

HENRY LAWRENCE GULLINE.
